UNITED STATES PATENT OFFICE

HOWARD J. KERR, OF WESTFIELD, NEW JERSEY, ASSIGNOR TO THE BABCOCK & WILCOX COMPANY, OF BAYONNE, NEW JERSEY, A CORPORATION OF NEW JERSEY

FURNACE AND METHOD OF OPERATING THE SAME

Application filed August 16, 1927. Serial No. 213,234.

My invention more particularly relates to a furnace and method of operating the same wherein a movable fuel bed is fed into the furnace, in which air is passed through the major portion of the fuel bed and air at a lower temperature is passed through the feed end of the fuel bed.

5

My invention will best be understood by reference to the accompanying drawing showing in side elevation, partially in section, a steam boiler and its setting and the associated parts, the drawing being somewhat diagrammatic.

I have illustrated my invention in conjunction with a steam boiler, which may be of any desired construction, and in the illustrated embodiment of which I have shown only a steam and water drum 10. The front wall of the setting is illustrated at 11, and 15 the rear wall thereof at 12, an ignition arch 13 being provided above the feed end of the device which moves the fuel bed into the furnace and which is here illustrated as a chain grate 14. A hopper 15 is provided in 20 the usual manner for supplying fuel to the feed end of the chain grate.

In the embodiment of my invention illustrated, a forced air blast is supplied to the furnace by a forced blast fan 16 from which 25 the air passes through a duct or passage 17, around the tubes 18 of an air heater 19, from the end of which the air is caused to pass through a duct 20 and distributed through passages 201 to the compartments 141 provided throughout the major portion of the chain grate stoker and from which the air passes upwardly through the fuel bed. The 30 temperature of the air passing over the tubes of the air heater is raised by the gases from the combustion chamber 21 which, after 35 passing over boiler heating surfaces, pass through the tubes 18 of the air heater.

In the embodiment of my invention illustrated, the heated air is also supplied to the compartment 142 at the front or feed end of the stoker, the supply of heated air to this and the other compartments being controlled by dampers 22. From the air heater, the 40 gases pass through a duct 23 to an induced

draft fan 24 from which the gases pass to the stack 25.

In accordance with my invention, air at a lower temperature is passed through the fuel bed at the feed or entrance end thereof than 55 that which is passed through the remaining major portion of the fuel bed.

In the embodiment of my invention illustrated, heated air may be forced into the front compartment 142 where other colder 60 air is mixed therewith. For this purpose, the cold air may be forced to the compartment 142 by the blower 16, a duct 26 communicating with the duct 17 between the blower 16 and the air heater 19. The amount 65 of cold air introduced to the front compartment 142 may be regulated by a damper 27 so that both the heated air and the cold air are introduced in regulated amounts, and the air passing from the compartment 142 70 through the entrance or feed end of the fuel bed may have any desired temperature.

By shutting the first damper 22 at the left of the figure and at the entrance end of the fuel bed and opening the damper 27, all of the air supplied to the first compartment 142 of the stoker would be cold air. By varying the positions of the dampers 22 and 27, the 75 temperature of the mixture of the heated and the cold air in the compartment 142, and hence the temperature of air passing through the feed end of the fuel bed, may be kept at any desired value.

Where all of the air forced into a chain 80 grate stoker has been heated, it has in some 85 cases and with certain kinds of coal caused an overheating of the entrance or feed end of the fuel bed with the result that the fuel bed at this portion becomes matted down so as to become more or less impervious to the air, and this action may be partially, at least, due to coking. Whatever the cause is, however, I have found in practice that the use 90 of air at a lower temperature at the entrance or feed end of the fuel bed than in the remaining portion thereof has resulted in better combustion and, therefore, better efficiency of the furnace with certain types of coal.

I claim:

1. The method of operating a furnace provided with a chain grate through which a forced blast of preheated air is passed which consists in mixing cooler air with the heated air at the entrance end of the chain grate.
2. The method of operating a furnace into which a fuel bed is movable and through which preheated combustion air is passed which consists in mixing a regulated amount of cold air with the heated air at the entrance end of the fuel bed.
3. The method of operating a furnace in which a fuel bed is movable which consists in preheating combustion air, forcing said preheated combustion air through a plurality of sections of the fuel bed, and forcing relatively colder air through the entrance section of said fuel bed.
4. The method of operating a furnace in which a fuel bed is movable which consists in preheating combustion air, forcing said preheated combustion air through a plurality of sections of the fuel bed and mixing cold air with the preheated air and then forcing the mixed air through the entrance section of said fuel bed.
5. The method of operating a furnace in which a fuel bed is movable which consists in preheating combustion air, forcing said preheated combustion air through a plurality of sections of the fuel bed, mixing cold air with the preheated air and then forcing the mixed air through the entrance section of said furnace, and regulating the relative amounts of hot and cold air in said entrance section.
6. In combination, a furnace, means for moving a fuel bed into the same, means for supplying combustion air to and passing it through the fuel bed, means for preheating said combustion air, and means for mixing cooler air with said combustion air at the entrance end of the furnace.
7. In combination, a furnace, a chain grate for moving a fuel bed into and through the furnace, means supplying combustion air to and passing it through the fuel bed, means for preheating said combustion air, and means for mixing cooler air with said combustion air at the entrance end of the chain grate stoker.
8. In combination, a furnace, means for moving a fuel bed into said furnace, means for supplying combustion air to and passing it through the fuel bed, means for utilizing the waste heat gases from the furnace for preheating the combustion air for the fuel bed, and means for mixing cooler air with said combustion air at the entrance end of the furnace.
9. In combination, a furnace, means for moving a fuel bed into the same, an air heater, means for passing the spent gases from the furnace through said air heater, a forced blast device for forcing air through

said air heater to and through the fuel bed, and means for leading a portion of the air from said forced blast device and before reaching said air heater to the entrance end of the fuel bed and mixing it with the heated air.

HOWARD J. KERR.
